UNITED STATES PATENT OFFICE.

JACOB SPAAR, OF KATONAH, NEW YORK.

MOUNTING FOR EYEGLASSES.

No. 930,895.

Specification of Letters Patent.

Patented Aug. 10, 1909.

Application filed November 18, 1908. Serial No. 463,323.

To all whom it may concern:

Be it known that I, JACOB SPAAR, a citizen of the United States, residing at Katonah, in the county of Westchester and 5 State of New York, have invented certain new and useful Improvements in Mountings for Eyeglasses; and I do hereby declare the following to be a full, clear, and exact description of the invention, such as will enable others skilled in the art to which it appertains to make and use the same, reference being had to the accompanying drawings, and to the characters of reference marked thereon, which form a part of this 15 specification.

This invention relates to new and useful improvements in eyeglass clip fasteners and the object in view is to produce a simple and efficient device of this nature, affording means whereby the screw holding the lens may be held from loosening, and comprises various details of construction, combinations and arrangements of parts which will be hereinafter fully described and then 20 specifically defined in the appended claims.

I illustrate my invention in the accompanying drawings, in which:—

Figure 1 is a perspective view showing the application of my invention to a lens, 30 and Fig. 2 is a sectional view through the same.

Reference now being had to the details of the drawings by letter, A designates a clip having fingers A' and A², the latter of 35 which is threaded for the reception of a screw B, and the former countersunk to receive the head of the screw similar to the usual fastening means commonly employed upon lenses. Projecting in opposite directions from the shank of said clip are the wings C and D, the former of which is provided with a threaded opening E for the reception of the screw F having an aperture G formed in the head thereof, whereby a pin 40 or other pointed instrument may be inserted therein for the purpose of turning the screw. H designates a lens held between the fingers by means of said screw B and the screw F is adapted to bear frictionally against the 45 50 marginal edge of the lens, as shown clearly in the sectional view of the drawings, and

serves to hold the marginal edge of the aperture O in the lens frictionally against the screw passing therethrough and serves to hold the latter from loosening. The 55 other of said wings, designated by letter D, is reinforced by means of the brace portion K fastened at one end to said wing D and its other end to the shank of the fastener adjacent to the forked portion R. This reinforcing brace is for the purpose of withstanding the strain which would come upon the wing D when the screw F is turned frictionally against the edge of the lens.

From the foregoing, it will be noted that, 65 by the provision of a lens mounted as shown and described, a simple and efficient means is afforded whereby a lens may be held securely and the screw upon which the lens is mounted prevented from loosening. 70

What I claim to be new is:—

1. A clip fastener for eyeglasses having apertured fingers, a screw carried thereby and engaging an eyeglass, wings upon the shank portion of said fastener, and a set 75 screw carried by one of said wings and adapted to bear against the edge of the eyeglass, as set forth.

2. A clip fastener for eyeglasses having apertured fingers, a screw carried thereby and engaging an eyeglass, wings upon the shank portion of said fastener, a set screw carried by one of said wings and adapted to bear against the edge of the eyeglass, the outer of said wings being reinforced, as set 80 85 forth.

3. A clip fastener for eyeglasses having apertured fingers, a screw carried thereby and engaging an eyeglass, wings upon the shank portion of said fastener, a set screw 90 carried by one of said wings and adapted to bear against the edge of the eyeglass, and an inclined reinforcing brace fastened at one end to the shank of the fastener and at its other end to said wings, as set forth. 95

In testimony whereof I hereunto affix my signature in the presence of two witnesses.

JACOB SPAAR.
